UNITED STATES PATENT OFFICE.

JAMES FORREST HOWE, OF WORCESTER, MASSACHUSETTS, ASSIGNOR TO THE AMERICAN STEEL AND WIRE COMPANY OF NEW JERSEY, A CORPORATION OF NEW JERSEY.

CABLE.

Application filed January 22, 1925. Serial No. 4,044.

This invention relates to cables and more particularly to ropes and cables primarily designed for use in supporting suspension bridges and the like, although it may be used wherever such a rope or cable is desirable.

5

One object of the present invention is to provide a flat rope composed of numerous small ropes or strands that may be used singly or in multiples to form a bridge or similar suspension.

Another object is to provide a flat rope that is particularly adapted to the formation of cables of large cross section for large bridge suspensions by laying several of such cables, one on top of the other, and securing them together.

A still further object is to provide a rope and cable having the novel features of construction, design, and combination of parts hereinafter described and claimed and illustrated in the accompanying drawings.

In the drawings, Figure 1 is a plan of a section of flat rope constructed in accordance with my invention.

Figure 2 is a side elevation thereof.

Figure 3 is an end elevation thereof.

Figure 4 is a top plan of a round cable constructed in accordance with my invention from a plurality of flat ropes such as shown in Figure 1.

Figure 5 is a cross section of the cable of Figure 4.

Figure 6 is a cross section of a square cable constructed in accordance with my invention.

Figure 7 is a diagrammatic elevation showing the adaption of my novel cable to bridge suspension.

40 Referring particularly to the drawings, the letter A designates the flat rope of Figures 1 to 3 as a whole, which is composed of a plurality of small rope strands 2, each of which is composed of a plurality of sub-strands 3, and each sub-strand is composed of a plurality of single wires 4. While I have shown each rope strand 2 composed of four sub-strands 3, it will be understood that any number of sub-strands 3 may be used within practical limits in forming the rope strands 2, and that any number of wires, within practical limits, may be used in forming the sub-strands.

The rope strands 2 are laid up spirally in

the usual manner, and each alternate one of the rope strands composing the rope A has a right hand lay, while the other rope strands of the rope have a left hand lay.

55 The rope strands 2 are laid in parallel relation, one beside the other, to form a rope of the desired width, and the several rope strands are secured together by a sewing strand 6 which is passed from side to side through the several rope strands in a zig-zag manner. The spaces between the sub-strands 3 form convenient openings through which the sewing strand may be and is usually passed.

60 In making up a heavy bridge cable, as for instance a twelve by twelve inch cable, any combination of the flat ropes A may be used. For example, twelve ropes A, each of which is twelve inches by one inch, may be used, or twenty-four ropes, six inches by one inch may be used, two of such ropes being used in each layer. Again twenty-four flat ropes twelve inches by one-half inch may be used. The combination of rope sizes that may be used to form any given cable cross section is almost unlimited. It will also be noted that by combining different widths and thicknesses of flat ropes A, an almost 65 unlimited variety of cross sectional cable shapes may be devised.

70 In Figures 4 and 5 I have shown a round bridge cable B composed of a plurality of flat ropes A constructed in accordance with my invention. The ropes A of the cable B are of gradually increasing thickness and width toward the center of the cable, so as 75 to form a more perfect circular cross section. The section of cable shown is provided with suitable wire seizing 8 at spaced intervals to bind the several ropes A together. It will be understood that this seizing may be continuous over the whole length of cable, if desired, or may be placed at spaced intervals as shown. If desired, the wire seizing may be dispensed with and suitable clamps substituted therefor, or the clamps and wire seizing may be used together to bind the 80 ropes together.

85 In the cable of Figures 4 and 5 I have also shown bolts or threaded rods 9 at spaced intervals and passing through the cable at right angles to the sewing wires or strand 6, and carrying washers 10 secured in place by nuts 11. These rods 9

serve as tie members and draw the several ropes A together.

In Figure 6 I have shown a cross section of a square cable B² composed of sixteen flat ropes A, each of which is composed of sixteen rope strands 2 and each rope strand 2 having four sub-strands 3. The ropes A each, therefore, have a width equal to the height of sixteen ropes A and when so combined form a square cable. The cable B² may be secured together by suitable wire or other seizing, such as described for the round cable B.

A stringer clamp 14 is shown on the cable B² provided with an attaching lug 15 adapted to have suitable vertical bridge stringers secured thereto.

In Figure 7 I have shown, diagrammatically, how my improved cable may be used. In this figure, 16 represents a cable constructed of several flat ropes, 17 represents the cable supports, and 18 the bridge girders. The cable 16 may have one or more of the clamps 14 secured thereto along its length to support stringers 19, which in turn are secured to the bridge girders 18.

The flat ropes A, forming the cable 16, are shown separated at each end and separately secured to suitable anchors 20, which are independently adjustable, as illustrated by turn buckles 21. In the illustration of Figure 7 only three ropes A are shown at each end of the cable, but it will be understood that the showing is only illustrative, and any number of ropes may be used in forming the cable, and that a separate anchor would be provided for each rope, although if found to be desirable or necessary, more than one rope may be secured

by each anchor and thus the number of 40 anchors reduced.

While I have illustrated certain embodiments of my invention, I do not wish to be limited thereto, since various modifications will readily suggest themselves to those skilled in the art and may be made without departing from the scope of my invention, as defined in the appended claims.

I claim:

1. A large bridge cable having a substantially circular cross section and composed of a plurality of flat ropes, laid one on top of the other, the center rope of the cable being of a width substantially equal to the diameter of the cable and each of the successive ropes on either side of the center rope being of less width than the preceding rope, and suitable seizing arranged at spaced intervals along said cable for securing said ropes together. 55

2. A large bridge cable having a substantially circular cross section and composed of a plurality of flat ropes, laid one on top of the other, the center rope of the cable being of a width substantially equal to the diameter of the cable and each of the successive ropes on either side of the center rope being of less width than the preceding rope, bolts passing through all of said flat ropes at spaced intervals along the length of said cable, and suitable seizing arranged at spaced intervals along said cable, said bolts and seizing securing said ropes together. 60 70 75

In testimony whereof, I have hereunto signed my name.

JAMES FORREST HOWE.
